FOLDING AND PRESSING MACHINE

Charles A. Price and Robert Russell Steward, Harrington, Del.; said Price assignor to said Steward

Application December 3, 1956, Serial No. 626,053

15 Claims. (Cl. 223—38)

This application relates to a machine for forming sheet material into parts having folded edges, and more particularly relates to a machine for folding and forming fabric into pockets in condition to be sewed upon an article.

A number of machines of this general type have heretofore been suggested. These existing machines may be divided into two general classifications. In one type of machine represented by the devices described in U.S. Letters Patent 2,317,817, 2,609,129 and 2,673,666, a lower pressing plate moves upward to compress the edge of the fabric looped about the edges of an upper forming plate against folding members whose upward movement is restrained by a frame.

Another type of existing machine is described in U.S. Letters Patent 2,238,048 and 2,453,623, and utilizes an upper template which is extracted from the folds to permit the folded edges of the blank to be pressed in position.

Both of these machines are relatively complicated and expensive to manufacture because of the complex movements which they incorporate.

An object of this invention is to provide a simple and economical machine for folding and fixing the edges of a blank of sheet material. Another object is to provide a machine of the type described which is simple, efficient and dependable in operation.

In accordance with this invention, a machine for folding and fixing fabric includes a base plate and a frame spaced a predetermined distance above and substantially parallel to the base plate. A pressing plate which passes within the inner border of the frame is mounted so that it can move through the frame against the base plate and also assume a position above and clear of the frame, and a pair of fabric-folding plates are supported between the frame and base plate a predetermined distance above the base plate. After a blank of fabric is pressed firmly against the base plate by the pressing plate with the edges of the fabric held upward by the inner border of the frame, the folding plates are moved towards the pressing plate to firmly drag and wedge the fabric into contact with the upper surface of the pressing plate. The edge of the fabric is, therefore, firmly squeezed against the base plate by the bottom of the pressing plate and against the top of the pressing plate by the lower edges of the folding plates. After the folding plates are retracted clear of the path of travel of the pressing plate, the pressing plate is moved upward to permit a folded and fixed blank of fabric to be abstracted from the machine.

The efficiency of the machine may be enhanced by heating the base plate and pressing plate by steam passages, for example, and by injecting a puff of dry steam into the creased portion of the fabric immediately prior to actuation of the folding plates. The folding efficiency of the folding plates and pressing plate are improved by tapering the edge of the pressing plate to a relatively sharp edge which helps define a sharp folding crease and assists in the dragging and wedging action of the folding plates.

It is especially desirable to actuate each of the motions in a predetermined sequence by means of a single lever in order to simplify and facilitate operation thereof. An operating mechanism of this type may include a cam member having projections: for moving the pressing plate upward and downward, opening and closing a steam injection valve, and for moving the folding plates inward and outward.

The aforementioned and other novel features and advantages of the present invention will become apparent to one skilled in the art from a reading of the following description in conjunction with the accompanying drawings wherein similar reference characters refer to similar parts and in which:

15 Fig. 1 is a top plan view of an embodiment of this invention;

Fig. 2 is a view in elevation of the embodiment shown in Fig. 1;

Fig. 3 is a bottom plan view of the embodiment shown in Fig. 1;

Fig. 4 is a cross-sectional view in elevation taken through Fig. 1 along the line 4—4, and looking in the direction of the arrows;

Fig. 5 is a rear view in elevation of a portion of the embodiment shown in Fig. 1;

Fig. 6 is a top plan view of the embodiment shown in Fig. 1 with the upper plate removed;

Fig. 7 is a view in elevation, partially in cross section, of a portion of the control portion of the embodiment shown in Fig. 1;

Fig. 8 is a view in elevation, partially in cross section, of the portion shown in Fig. 7 in another phase of operation;

Fig. 9 is a sectional view, partially in cross section, of the portion shown in Figs. 7 and 8 in still another phase of operation;

Fig. 10 is a plan view of a pocket folded and fixed by means of the embodiment shown in Fig. 1;

Fig. 11 is a cross-sectional view in elevation showing the relative positions of the folding and pressing plates prior to their inward movement; and

Fig. 12 is a cross-sectional view in elevation of the apparatus shown in Fig. 11 after the folding plates have moved inward.

In Figs. 1 and 2, a machine 10 is shown prior to operation with the pressing plate 12 elevated over and clear of frame 14 which is spaced a predetermined distance above a base plate 16. Pressing plate 12 is small enough to pass through the inside border 18 of frame 14 to contact the top of base plate 16.

Pressing plate 12 is mounted upon a head 20 which is secured to arm 22 which is secured upon shaft 24 which pivots upon pointed ends of rods 26 secured to brackets 28 attached to the base 30 of the machine. Base 30 also supports the aforementioned frame 14 and base plate 16. All parts of this machine which require structural strength and rigidity are formed of a noncorrosive material such as stainless steel. Other portions of the machine which do not require high force resistant properties may be made of aluminum. Where steam piping is used, it may advantageously be formed of noncorrosive tubing such as brass or copper.

Referring to Fig. 3 in conjunction with Figs. 1 and 2, means are provided for supplying a flow of steam to the head 20 and to a plate 32 underlying base plate 16. Plates 16 and 32 may, if desired, be formed as a single unit, but fabrication is facilitated by making them as two separate pieces which are then joined to each other. Since plate 16 is in contact with the fabric, it should be made of stainless steel, whereas plate 32 may be made of ordinary carbon steel or brass for example.

Steam is supplied to the machine by means of inlet pipe 34 and drained by means of outlet pipe 36. Steam is supplied to the upper head 20 by means of a flexible hose 38 which connects to main inlet 34 at T 40. Steam is supplied to internal cavity 42 of head 20 by means of tubing 44 inserted within arm 22. Steam is drained from cavity 42 by tubing 46, flexible hose 48 and enters the main drain pipe 36 through T 50.

Main supply pipe 34 continues through to the remote end to base 30 whereupon it enters the side of block 32 through elbow 52 for example. Referring particularly to Fig. 3, the steam is conducted through passage 54 within block 32 which is drained at the bottom of block 32 by means of drain pipe 56 which joins the main drain pipe 36.

A supply of relatively dry steam is abstracted from passageway 54 adjacent the inlet to block 32 by means of a pipe 58 connected to the upper side of passageway 54. Pipe 58 conducts this relatively dry steam to valve 60 which is connected by means of passageway 62 to a U-shaped groove 64 in the upper surface of block 32 which supplies a flow of steam to the corresponding U-shaped row of apertures 66 (Fig. 6) within plate 16 which lie within the border 18 of frame 14. Passage 58 extracts relatively dry steam because the heavier water particles tend to follow the straight path of motion past the inlet to pipe 58 as the wet steam is discharged from elbow 52 through passageway 54. The relatively dryer and lighter steam having less momentum can pass into passage 58.

Valve 60 is a plunger operated valve, for example, and includes an elongated stem 68 which communicates with a cone-shaped piston 70 which seats to seal the valve when stem 68 moves in a direction away from the valve for example. Stem 68 is urged into the closed position by means of a coil spring 72 which reacts between a projection on stem 68 and the face of valve 60. The remote end of stem 68 terminates in a screw 74 which may be adjusted to vary the time and duration of the opening of valve 60. Stem 68 is actuated by means of a pawl-like lever 76 pivoted upon cam 78 by means of a shouldered pin 80 for example. Pawl-like lever 76 is maintained in contact with projection pin 82 by means of tension spring 84. Lever 76, therefore, strikes the screw 74 at the end of stem 68 to actuate valve 60 as it moves toward the head of screw 74, but is allowed to pivot out of the way of the head of screw 74 as it moves away from it so that the valve is not actuated on the return movement of the lever.

Cam 78 is secured to shaft 86 which rotates within bearings in brackets 28 secured to frame 30. Shaft 86 extends to one side of brackets 28 where it is joined by operating handle 88. Rotation of operating handle 88, therefore, rotates cam 78 which includes projections for operating each of the elements of the machine in proper time sequence to fold and fix a fabric blank. In addition to the aforementioned pawl-like lever 76 for actuating steam valve 60, cam 78 includes a surface for cooperating with follower or roller 90 to move arm 22 up and down and also includes projections or pins 92, 94 and 96 for moving the folding plates towards and away from each other.

For rotating arm 22 upward and downward to bring pressing plate 12 into contact with the base plate 16 and to move it away and free of the base plate to permit blanks of fabric to be placed or inserted into the machine, a lever 98 is firmly secured to pivoted shaft 24 which is also fastened to arm 22. Roller or follower 90 is rotatably mounted on arm 98 and rides upon the specially shaped surface of cam 78 to raise and lower arm 22 at designated periods. Cam 78 includes a deep depression 100 within which roller 90 drops to raise arm 22 and maintain it in a raised condition while blanks are loaded into the machine. This deep recess 100 maintains arm 22 securely locked in a raised condition in cooperation

with the downward pulling action of tension spring 102 connecting lever 98 to a lower point of base 30. Cam 78 includes a rising surface 104 extending from recess 100 which causes roller 90 to rise as the cam is rotated by a backward movement of handle 88. As roller 90 rises upon surface 104, it causes arm 22 to rotate downward which brings pressing plate 12 into contact with base plate 16.

Shortly after roller 90 moves upward out of recess 100 and over hump 104, pawl-like lever 76 strikes the head of screw 74 at the end of valve stem 68 to momentarily open the valve to admit a puff of steam to a blank maintained in contact with plate 16 and over aperture 66 (Fig. 8).

5 Prior to this time, pin 92 which initially was in contact with the outside of folding plate operating lever 106 to maintain it pivoted about shaft 24 in a direction to move rod 103 towards the front of the machine and consequently to open folding plates 110, moves away from lever 106 to permit stem 108 to be moved towards the back of the machine to permit folding plates 110 to move towards each other and close. When cam 78 is, therefore, rotated from the position shown in Fig. 7 to the position shown in Fig. 8, pins 94 and 96 assume positions on either side of lever 106 with pin 94 starting to contact inside of lever 106. After cam 78 has rotated to the position shown in Fig. 9, pin 96 has moved against lever 106 to rotate it away from the machine and to close folding plates 110 by means of rod 108 in a manner later described in detail. When cam 78 is rotated in the opposite direction by a forward pull on operating handle 88, pin 94 strikes the outside of lever 106 to move it towards the machine and to open folding plates 110. When the operating handle 88 is moved to the fully forward position with roller 90 lying within recess 100 (Fig. 7), pin 92 once more maintains lever 106 securely pivoted towards the machine to maintain folding plates 110 fully open.

40 Folding plates 110 are mounted within a predetermined space 112 between frame 14 and base plate 16 (see Figs. 4, 11 and 12). Folding plates 110 are maintained a predetermined distance above the surface of plate 16 by means of spacers 114. Referring to Fig. 6, it is seen that folding plates 110 and spacer plates 114 which they 45 overlie, are substantially L-shaped; with their inner edges lying adjacent the inner border 18 of frame 14. Spacer plates 114 are maintained in position upon base plate 16 by pins 118 extending through corresponding round holes in plates 114. Folding plates 110 are guided by pins 118 which extend through elongated diagonal slots 120 in folding plates 110. Adjacent ends of folding plates 110 overlap as shown at 122 with areas of reduced thickness to lie flat within the predetermined space even when overlapped. The ends of spacer plates 114, however, terminate short of each other to avoid the problem of overlapping.

50 Referring to Fig. 6, the two phases of movement of folding plates 110 are shown with the opened condition shown in full line and the closed condition shown in broken line. Plates 110 are moved from the opened to the closed position by means of a linkage including a cross link 124 which is connected to the ends of folding plates 110 by means of connecting links 126. Movement of cross link 124 towards the front of the machine 55 opens plates 110 whose movements are guided by pins 118 and slots 120, and backward movement of cross link 124 closes plates 110 accordingly.

The forward and backward movement is imparted to cross link 124 from rod 108 and lever 106 by means of angular bracket 128 attached to rod 108. Angular bracket 128 is secured to block 130 which rides within slot 132 in base plate 16 by means of screws 134 which also secure cross link 124 to bracket 128. Backward and forward movement of rod 108 respectively closes and 75 opens folding plates 110.

Pins 118 perform an additional function to that of orienting plates 110 and 114. The upper surfaces of pins 118 support frame 14 a predetermined distance 112 above base plate 16 (see Figs. 11 and 12). Pins 118 are screwed, for example, into base plate 16 to permit their extension above plate 16 to be varied. This permits variation of space 112 to adjust the machine for fabrics of varying thickness. Plates 110 and 114 are easily removed by lifting away from pins 118 to permit replacement by plates of accordingly varying thicknesses. Adjustment of the machine may easily be achieved by adding additional spacer plates 114 or replacing the original plates 114 by plates of different thicknesses.

Operation

Prior to insertion of a blank of fabric the machine is in the position shown in Figs. 1 and 2 with operating handle 88 extending in a forward position with arm 22 raised. A blank of fabric 136 is placed over the border 18 of frame 14 and lever 88 is pushed away from the operator which moves arm 22 downward into the position shown in Fig. 4 with pressing plate 12 maintaining the fabric pressed against base plate 16, as shown in Fig. 11, and the outer edges 138 of the blank of fabric 136 held upward by border 18 of frame 14. Continued movement of handle 88 away from the operator to the position shown in Fig. 8 causes pawl-like lever 76 to momentarily strike the head of screw 74 at the end of valve operating stem 68 which admits a puff of steam through apertures 66 which permeates the fabric adjacent the edge of pressing plate 12. The edge of pressing plate 12 is preferably tapered to a relatively sharp point to aid in creasing the fabric which facilitates folding and fixing. Since pressing plate 12 and base plate 16 are both heated preferably by steam to avoid scorching, it is not absolutely necessary to permeate the fabric with jets of steam through aperture 66, but admission of steam facilitates and improves the efficiency of the fixing and pressing operation.

When the lever is moved still further backward to the position shown in Fig. 8, valve 60 is closed and pin 96 starts to contact the inside of lever 106 which commences the closing movement of folding plates 110. At this time, roller 90 has moved up a slight incline on cam 78 to firmly squeeze fabric 136 against base plate 16 by downward pressure of plate 12. The slight incline on cam 78 provides considerable mechanical advantage for application of this pressure thereby permitting an operator to apply this pressure with expenditure of minimum force.

In Fig. 9, pin 96 has finished its outward movement of lever 106 which fully closes folding plates 110 with pressing plate 12 firmly maintaining fabric 136 in contact with base plate 16. As shown in Fig. 12, folding plates 110 have moved towards each other and over the edges of pressing plate 12 and firmly drag and wedge the folded edge of the fabric into contact with the edges and upper surface of pressing plate 12. This dragging and wedging movement positively creases the folded edge and presses it in contradistinction to prior art operations which merely squeeze or press the fold. The tapered edges of pressing plate 12 assist in this dragging and wedging movement which unexpectedly provides accurately folded and firmly fixed folded blanks such as pockets shown, for example, in solid line in Fig. 10.

An operator, accordingly can easily operate this machine with minimum expenditure of effort to provide a great number of accurately folded and firmly fixed pockets. This operation is facilitated by the single lever operation which has heretofore been unachieved in a hand-operated machine. This single lever operation is made extremely easy by the lack of springs acting in opposition to the operating movements of the operator.

What is claimed is:

1. A machine for folding and fixing fabric compris-

ing a heated stationary base plate, a frame spaced a predetermined distance above and substantially parallel to said base plate, a pressing plate slightly smaller in area than the inner border of said frame and having a relatively thin edge which is thinner than said predetermined distance, movable means upon which said folding plates are mounted which permit it to move from a position above and free of said frame through said frame against said base plate to hold a blank of fabric firmly against said base plate with its edges maintained extending upwardly by the inner border of said frame, a pair of fabric-folding plates supported to slide in a confined path between said frame and said base plate to provide forceful sliding contact with the adjacent surface of said frame, means for moving said fabric-folding plates toward each other over the edges of said pressing plate, the edge of said pressing plate being tapered to form a sharp outer edge at its periphery to allow said fabric-folding plates to sharply crease said fabric around the edge of said pressing plate, apertures being provided in said base plate adjacent the periphery of said edge of said pressing plate for directing a flow of steam against the edge of said fabric folded over said pressing plate by said fabric-folding plates to permit the crease in said fabric about the edge of said pressing plate to be fixed as said fabric-folding plates move together and drag and firmly press the edges of said fabric over and against said pressing plate, means for providing a flow of steam to said apertures, and means for moving said folding plates away from each other and clear of the path of travel of said pressing plate to permit said fixed and folded fabric to be removed from said pressing plate.

2. A machine as set forth in claim 1 wherein spacing plates are provided between said folding plates and said base plate to maintain said folding plates in firm sliding contact with the lower surface of said frame a predetermined distance above the upper surface of said base plate.

3. A machine for folding and fixing fabric comprising a heated base plate, a frame spaced a predetermined distance above and substantially parallel to said base plate, a pressing plate slightly smaller in area than the inner border of said frame and having a relatively thin edge which is thinner than said predetermined distance, movable means upon which said folding plates are mounted which permit it to move from a position above and free of said frame through said frame against said base plate to hold a blank of fabric firmly against said base plate with its edges held upward by the inner border of said frame, a pair of fabric-holding plates supported between said frame and said base plate a predetermined distance above said base plate, means for moving said folding plates towards each other over said pressing plate against said upward held edges of said fabric to firmly drag and wedge said fabric into contact with the edges and upper surface of said pressing plate, means for moving said folding plates away from each other and clear of the path of travel of said pressing plate, said folding plates being comprised of a pair of L-shaped plates whose motion towards and away from each other is guided by pins mounted in said base plate and inserted through diagonal slots in said folding plates, and the height of said pins being variable to permit adjustment of the distance between said base plate and said frame for accommodating folding plates of varying thickness to permit folding of fabric over a range of thicknesses.

4. A machine as set forth in claim 3 wherein a reciprocating linkage is connected to said L-shaped members by means of pivoted links to provide a positive movement of said folding plates towards and away from each other.

5. A machine as set forth in claim 1 wherein said means for providing steam to said apertures is comprised of a tangential off-take from said steam supply to said base plate to provide a substantially dry supply of steam to said apertures.

6. A machine as set forth in claim 3 wherein said pins for guiding the movement of said folding plates are straight sided to facilitate replacement of said folding plates.

7. A machine for folding and fixing fabric comprising a heated base plate; a frame spaced a predetermined distance above and substantially parallel to said base plate; a pressing plate slightly smaller in area than the inner border of said frame and having a relatively thin edge which is thinner than said predetermined distance; movable means upon which said folding plates are mounted which permit it to move from a position above and free of said frame through said frame against said base plate to hold a blank of fabric firmly against said base plate with its edges held upward by the inner border of said frame; a pair of fabric-folding plates supported between said frame and said base plate a predetermined distance above said base plate; means for moving said folding plates towards each other over said pressing plate against said upward held edges of said fabric to firmly drag and wedge said fabric into contact with the edges and upper surface of said pressing plate; means for moving said folding plates away from each other and clear of the path of travel of said pressing plate; said base plate being mounted upon said frame; a shaft being rotatably mounted upon said frame; said shaft including actuating means operatively connected to said movable means for raising and lowering said pressing plate, to a valve for operating said steam injecting apparatus, and to a means for operating said folding plates; and a single lever is connected to said shaft to permit operation of said members in operative sequence by a single motion.

8. A machine as set forth in claim 7 wherein a cam is mounted upon said shaft and said pressing plate is secured to an arm pivoted upon said frame, a follower in contact with said cam being connected to said arm and the surface of said cam including a recess for holding said follower in position to maintain said arm in a raised condition, and said cam including a surface formed to actuate said follower to bring said pressing plate into intimate contact with said base plate upon rotation of said operating lever and said cam.

9. A machine as set forth in claim 8 wherein said follower is comprised of a roller.

10. A machine as set forth in claim 8 wherein said cam includes a pawl-like projection which strikes the operating extension of said valve upon rotation of said cam immediately prior to inward movement of said folding plates.

11. A machine as set forth in claim 8 wherein a folding-plate actuating lever is pivoted to said frame, said cam including three pins, one of said pins contacting said lever to maintain said folding plates positively open when said arm is raised, the second pin contacting the other side of said lever to drive said lever in a direction to close said folding plates during the last phase of rotation of said cam, and the third pin contacting the first mentioned side of said lever to positively open said folding plates when said lever is moved in a direction to raise said arm.

12. A machine as set forth in claim 11 wherein said arm, said follower and said folding-plate operating lever are secured to an auxiliary shaft which is pivotally mounted upon said frame.

13. A machine as set forth in claim 8 wherein the initial movement of said cam raises said roller out of

said recess in position to lower said arm to bring said folding plate in contact with said base plate, said pawl-like lever being positioned to then momentarily contact said valve extension to admit a puff of steam through said apertures to the portion of said fabric adjacent the edge of said pressing plate, said pins for positively closing and opening said folding plates then rotating to loosely grasp said folding plate operating lever therebetween, in the final phase of said cam said surface including a slight rise to force said pressing plate firmly against said base plate with ease of operation by virtue of mechanical advantage, said second pin being positioned to contact the inner surface of said folding-plate operating lever to close said folding plates, and said pawl-like projection being resiliently secured against an abutment to permit said pawl-like projection to ride over said valve extension without actuating it when said cam is rotated to raise said arm.

14. A machine for folding and fixing fabric comprising a heated base plate, a frame spaced a predetermined distance above and substantially parallel to said base plate, a pressing plate slightly smaller in area than the inner border of said frame and having a relatively thin edge which is thinner than said predetermined distance, movable means upon which said folding plates are mounted which permit it to move from a position above and free of said frame through said frame against said base plate to hold a blank of fabric firmly against said base plate with its edges held upward by the inner border of said frame, a pair of fabric-folding plates supported to slide in a confined path between said frame and said base plate to provide forceful sliding contact with the adjacent surface of said frame, the edge of said pressing plate being constructed and arranged to maintain a fold of fabric turned around said edge and firmly pressed between the surfaces of said folding plates and said base plate which are disposed adjacent said pressing plate, means for moving said folding plates towards each other against said upward held edges of said fabric to firmly drag and wedge said fabric into contact with the edges and upper surface of said pressing plate to fix a fold in said fabric, means for moving said folding plates away from each other and clear of the path of travel of said pressing plate to permit said folded fabric to be removed from said machine, and said folding plates being comprised of flexible plates which are thin enough to permit a slight resilient yielding as said fabric is dragged and pressed into close engagement with the upper surface of said pressing plate.

15. A machine as set forth in claim 14 wherein the engaging surfaces of said pressing plate and said fabric-folding plates are cooperatively tapered to facilitate the drawing and pressing of said fabric into close engagement with the upper surface of said pressing plate by said fabric-folding plates.
